UNITED STATES PATENT OFFICE.

EDWARD G. KINSLEY, OF STOUGHTON, MASSACHUSETTS.

IMPROVEMENT IN FLEXIBLE SOLES.

Specification forming part of Letters Patent No. 33,436, dated October 8, 1861.

To all whom it may concern:

Be it known that I, EDWARD G. KINSLEY, of Stoughton, in the county of Norfolk and State of Massachusetts, have invented a new and useful or Improved Sole for a Shoe or Boot; and I do hereby declare the same to be fully described in the following specification and illustrated in the accompanying drawings, of which—

Figure 1 is a view of the grooved side of it, while Fig. 2 is a transverse section, and Fig. 3 a longitudinal section, of it.

My invention is an improved arrangement of a sheet of rubber or flexible material of like nature and a series of edge and connecting metallic plates, the whole being substantially as hereinafter described.

In the drawings, A exhibits the sheet of caoutchouc, while B C D are the edge-plates, and E E E the transverse connecting-plates. The sheet of rubber not only has the form of the sole or part of the shoe to which it is to be affixed, but is made with a series of projections *a a a a* to extend through, and a little beyond the spaces 'A', which are to be made between the several metallic plates, which have the form as shown in the drawings. Each two side plates D D are joined together by a bar or flat plate E, each plate D on each side of the sole being separate from and arranged with respect to the other plates D D on the same side, as shown in Fig. 1. The end plates B and G are curved to fit the ends of the sheet A, all the said plates being made to rest flatwise against the said sheet and are to be secured to the sheet and so as to fasten

both it and them to the sole of a shoe by means of screws passed through holes *b b b* and screwed into such sole. When the sole so made of a series of metallic plates and a sheet of elastic rubber formed with projections, as set forth, is fastened to a shoe the joints between the plates will permit the sole to have the necessary flexibility. While the plates, and particularly those marked E, will protect the rubber from wear, the parts *a a* of it which are between the plates will serve to prevent the shoe from slipping while treading on ice or snow.

I am aware that a flexible sole has been composed of pieces of rubber and separate frames or sockets fastened to a sole, in which case not only was the rubber cemented to the sole, but the frames extended from the sole and downward against the edges of the rubber, the whole being arranged in manner as exhibited in the United States Patent No. 29,344, granted July 24, 1860. Therefore I do not claim such an arrangement of metal and either rubber or gutta-percha, as such differs materially from my improved arrangement of rubber and metal plates.

I claim—

The series of metallic plates B, C, D, and E, in combination with the rubber sole A A', the whole being constructed and arranged substantially in manner as described.

EDWARD G. KINSLEY.
